UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING-MACHINE.

1,400,702.

Specification of Letters Patent. Patented Dec. 20, 1921.

Original application filed March 20, 1918, Serial No. 223,489. Divided and this application filed December 13, 1919. Serial No. 344,686.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to typewriting machines, and more especially to the ribbon-vibrating mechanism for such machines, and is herein disclosed as applied to a machine having two sets of type-bars adapted to print at different printing points, and embodying many of the features of the Underwood standard typewriting machine.

This application is a division of my pending application, Serial No. 223,489, filed March 20, 1918 (now Patent No. 20 1,340,925, dated May 25, 1920). In machines of this and other types, it is frequently advantageous to have two ribbon-carriers, which may be alternatively vibrated to bring a ribbon to the printing 25 point, one carrier being idle, while the other is being vibrated.

According to the present invention, there may be provided a single actuator, which is adapted to engage either of two vibrating 30 levers, one vibrating lever serving to actuate one ribbon-carrier, and the other serving to actuate the other ribbon-carrier. Where the machine embodies two sets of type-bars, there may be a separate universal bar for 35 each set of type-bars, and the actuator may engage with either of said universal bars. In order to hold the vibrating lever against sidewise movement, during the shifting operation, each vibrating lever may be guided 40 by a bracket or member projecting from the segment which carries the type-bars. If the machine embodies a case-shift which shifts the platen, there may be provided means to insure engagement of the actuator 45 with the vibrating lever irrespective of the position of the vibrating lever, this being usually useful since the fulcrum of the vibrating lever usually shifts with the case-shift. Means may be provided for supporting each ribbon-carrier, so that it does not drop when its vibrating lever is disengaged from the actuator.

Other features and advantages will hereinafter appear.

In the accompanying drawings,

55

Figure 1 is a plan view, largely diagrammatic, of an Underwood standard typewriting machine having two sets of type-bars, and showing my invention applied thereto.

Fig. 2 is a sectional side view of the same. 60

Fig. 3 is a skeleton perspective rear view, showing the ribbon-vibrating mechanism.

In carrying out my invention, I have mounted two type-sets 10 and 10^a in front of a platen 11, either one of which may be 65 moved into effective relation therewith. Said type-sets comprise type-bars 12, which may be swung to print against the platen through the intermediary of bell-crank 13, actuatable by sub-levers 14. The free ends 70 of the sub-levers 14, of which there are two sets, one associated with each type-set, project forwardly under hook-like portions 15 on keys or key-levers 16, so that they may be actuated by said key-levers and moved relatively thereto when changing from one type-set to another.

To conveniently change from one type-set to another, the type-bars 12 are mounted on two type-bar segments 17, which are supported by a cross-bar 18, forming part of a type-carrying truck 19 which is guided by a rail 20, extending in the direction of the platen and secured to the machine frame 21. The type-carrying truck 19 may be moved 80 from side to side of the machine frame 21, to render either type-set effective with the platen, and to move the free ends of the sub-levers 14 into effective relation with the engaging portions 15 of the key-levers 16. 85 This may be done by means of a finger-piece 22, forming part of the type-bar-rests 23, secured to the type-carrying truck 19. 90

The bell-crank 13 and the sub-levers 14, associated with the type-bars 12 of both type-sets, are pivotally supported on slotted cross-bars 24 and 25, respectively, secured to the type-carrying truck, so that they may be actuated thereon.

Each sub-lever 14 has associated therewith a return-spring 26, to restore the connected type-bar 12 to its normal position, upon the return of the key-lever 16; the latter being restored to its normal position by a spring 27.

The key-levers 16 are pivoted on a common fulcrum-rod 28, supported on a slotted cross-bar 29, secured to the machine frame 21. The key-levers extend forwardly beneath the sub-

levers 14, out of the path of travel of the type-carrying truck 19 and the sub-levers 14 carried thereby, when the free ends of the latter are moved into engaging relation with 5 the hook-shaped portions 15 on said key-levers 16.

To maintain the effective relation between the key-levers 16 and the sub-levers 14, or, in other words, to guard against disengagement 10 between said levers, during an actuation thereof, slotted guide-plates 30 and 31 are provided for the key-levers 16 and the sub-levers 14, respectively, which avoid any possible sidewise motion of said levers relative to each other while being actuated. The 15 guide-plate 30 for the key-levers 16 is preferably secured to the machine frame 21, while the guide-plate 31, which guides the forward ends of the sub-levers 14, is secured to the type-carrying truck 19 by means of suitable 20 brackets 32 extending forwardly therefrom.

To facilitate the movements of the type-carrying truck 19, anti-friction balls 33 are provided, which play in raceways 34 formed 25 by grooves in the fixed rail 20 on the machine frame, and grooves in a rail 35 secured to the type-carrying truck 19.

By an inspection of Fig. 2, it will be seen that most of the mechanism, carried by the 30 type-carrying truck 19, is supported in front of the guide-rail 35 thereof. Thus, there is an overhang which has a tendency to turn the rail 35 within the rail 20 and cause unnecessary binding. To guard against such 35 action, I have provided a guide-rail 36, extending underneath the type-carrying truck 19, with which one or more rollers 37 may engage, said rollers being rotatably supported on the slotted cross-bar 25 of said truck.

40 The type-carrying truck 19 is normally locked, to prevent accidental displacement, by means of a pawl 38 which normally engages in one of two slots 39 and 40, Fig. 1, according to which type-set is effective; said 45 slots being formed in the cross-bar 25 of the truck 19. When it is desired to change from one type-set to another, as for example from type-set 10 to type-set 10^a, the pawl 38 is moved out of the slot 39 by means of a handle 50 or finger-piece 41, Fig. 2, pivotally mounted at the left-hand side and at the front of the machine frame 21. The handle is swung about its pivot 42 to draw on a link 43 connected with an arm 44, projecting downwardly from a rock-shaft 45, upon which the pawl is mounted. Said finger-piece 41 is moved until it strikes a fixed stop 46, at which time the pawl has been moved out of the slot 39. The type-carrying truck is then 55 moved rightwardly a trifle until the slot 39 is out of alinement with the pawl 38, at which time the operative may let go of the finger-piece controlling the pawl, when a return-spring 47 becomes effective to hold the pawl 60 38 against a back 48 formed between the slots

39 and 40, on the bar 25. A continued movement of the type-carrying truck, by means of the handle secured thereto, is then effected until a stop 49, projecting rearwardly from the slotted cross-bar 25 on said truck 19, 70 comes into engagement with the pawl 38, at which time the pawl also drops into the slot 40 by the influence of the return-spring 47, and the handle 41 moves back against a fixed stop 50. Thus, the left-hand type-set is 75 brought into effective relation with the platen, and is accurately positioned by means of the stop, and locked in said position by means of the pawl 38, without any special attention of the operative. To facilitate the 80 entrance of the pawl 38 into the slots 39 and 40, the pawl or the slots may be provided with beveled edges.

The platen 11 is mounted on a platen frame 51, supported for case-shifting movements, 85 hereinafter described, on a carriage 52, which is arranged to travel for letter-feeding movements, during typing operations, on a front rail 53 and a rear rail 54 secured to the machine frame 21.

The letter-feeding movements of said carriage are controlled by an escapement comprising an escapement wheel 55, which is geared to the typewriter carriage 52 by means of a pinion 56 and rack 57 meshing therewith; said rack being pivotally supported at 58 on said carriage 52. A suitable spring-drum 59 constantly urges the carriage 52 leftwardly, and thus tends to rotate the escapement wheel 55, which is provided with teeth 60, engaging with a loose dog 61 and a fixed dog 62 on a dog-rocker 63 which is caused to vibrate back and forth each time a type-bar 12 is caused to print.

To do this, each type-bar is provided with 105 a heel 64, which, as the type-bar approaches the printing point, engages with a universal bar 65 to move the latter rearwardly to transmit said movement by means of a cross-bar 66 thereon, Fig. 2, to a floating interponent 67, provided with a cross-bar 68 which engages with the dog-rocker 63 to move the latter against the tension of a return-spring 69; thus freeing the loose dog, so that it may be moved by a spring 70, Fig. 3, to bring 110 it into effective relation with the next tooth 60 of the escapement wheel 55. At the same time the fixed dog moves into holding relation with the tooth 60 just disengaged by the loose dog 61. When the type-bar leaves the platen to return to its normal position the universal bar and the interponent are restored to their normal positions by suitable springs 71 and 72, respectively, Fig. 2. Thus, the dog-rocker is permitted to return 115 to normal position under the influence of its spring 69 to move the fixed dog 62 out of engagement with the escapement wheel 55 and bring the loose dog 61 into engagement with the next tooth on the escapement 120 125 130 135 140 145 150 155 160 165 170 175 180

wheel whereupon the latter moves until the loose dog 61 is arrested by a fixed stop 72^a on the dog-rocker 63, thereby effecting a letter-space movement of the carriage 52.

- 5 It should be understood that only a single escapement is used, and that said escapement is actuatable through the intermediary of the floating interponent 67, which may be actuated by the universal bars 65 associated with 10 the type-sets 10 and 10^a, each universal bar being supported in back of the segment which supports the associated set of type-bars of the corresponding type-set. Each 15 universal bar is brought into effective relation with said interponent when the corresponding type-set is rendered effective.

Each universal bar 65 is mounted for parallel movement by suitable guiding means, said guiding means comprising a rock-shaft 20 73, Fig. 3, pivotally supported on ears 74 secured to the cross-bar 18. Said rock-shaft 73, when moved, swings two downwardly-projecting arms 75, secured thereto, to move the universal bar 65, pivotally connected to 25 their ends, by means of ears 76, extending upwardly from the cross-bar 66 of said universal bar. The lower part of the universal bar 65 is also moved rearwardly through the intermediary of an arm 77 projecting rearwardly from the rock-shaft 73, which swings a bell-crank 78, connected thereto and pivotally mounted on a bracket 79 secured to the type-bar segment 17. A downwardly-projecting arm 80 of said bell-crank moves 30 the lower part of the universal bar, to which it is pivotally connected by means of an ear 81, secured to the lower part of said universal bar.

The interponent 67, through the intermediary of which the dog-rocker 63 is vibrated, 40 may be guided by a swinging frame 82, Fig. 3, comprising a rock-shaft 83, pivotally supported on a bracket 84, upon which the dog-rocker 63 and the escapement wheel 55 are 45 also supported. Said rock-shaft 83 has two upwardly-extending arms 85, to which the rear end of the interponent 67 is pivotally connected by ears 86 extending from the cross-bar 68 of said interponent. The forward end of said interponent is supported 50 by a link 87, pivoted on the bracket 84, and arranged to move parallel with the arms 85 extending upwardly from the rock-shaft 83.

A space-bar 88 may be used to actuate the 55 escapement mechanism. Said space-bar may comprise two rearwardly-extending arms, in the form of levers 89, pivoted to swing on the fulcrum-rod 28. Said levers project upwardly beyond the fulcrum 28, and are bent 60 toward each other, to the center of the machine, where they are joined to form an upwardly-projecting arm 90, which engages with a downwardly-projecting arm 91 on the rock-shaft 83 of the swing frame 82, to 65 rock the latter and actuate the dog-rocker 63,

through the intermediary of the interponent 67, thus vibrating the loose and fixed dogs thereon, between the teeth of the escapement wheel 55, to effect a letter-space movement of the carriage in a manner hereinbefore described. It will be understood with this arrangement, that the escapement may be actuated, by the space-bar, without idly actuating the universal bar 65.

The platen 11 may be shifted from lower-case to upper-case position to facilitate typing with lower-case and upper-case types 75 92 and 93, respectively, by suitable shift-key-levers 94, of which there may be one arranged at each side of the machine. Each 80 shift-key-lever 94 may be pivotally supported on the fulcrum-rod 28, and, when depressed, causes an upwardly-projecting arm 95 thereof to swing forwardly, and rock a shift-frame 96 through the intermediary of 85 an arm 97 projecting downwardly from a rock-shaft 98, forming part of said shift-frame 96. Said shift-frame 96 also comprises forwardly-projecting arms 99, supporting at their forward ends a shift-rail 100, which moves bodily upward when 90 said shift-frame 96 is actuated, thus moving the platen-frame 51, with the platen 11, to upper-case position through the intermediary of a roller 101 secured to a cross-bar 102 on said platen frame, said roller 101 being adapted to roll on said shift-rail 100 during letter-space movements of 95 said platen. Said platen frame 51 is guided in its shifting movements by links 103 projecting forwardly from a rock-shaft 104 on the carriage 52. Said rock-shaft 104 may be provided with a counterbalance spring (not 100 shown), as in the Underwood typewriting machine, to facilitate the shifting movements 105 of the platen 11. Return-springs, similar to the return-springs 27 for the key-levers 16, may be provided for the case-shift-key-levers 94.

A ribbon 105 is provided, through which 110 the types print, Fig. 1. Said ribbon passes from one to another of two ribbon-spools 106 and is guided over rollers 107 arranged near said spools. Said ribbon 105 is also threaded through ribbon-vibrators 108, of which 115 there is one for each type-set; each vibrator 108 being arranged in back of a type-bar guide 109 for the type-bars 12 of each type-set. A central roller 110 is provided to guide said ribbon 105, so that the sections of 120 ribbon disposed between said central roller 110 and the rollers 107, located at the ribbon-spools, may be vibrated, one independently of the other, when its associated type-set is effective. It will be seen that the guide-rollers 125 107 are mounted on ribbon-spool casings, which contain the ribbon-spools 106, the casings being secured to brackets 112 on the type-carrying truck 19; also that the central roller 110 is mounted on a central support 130

113 for the type-rests 23. Thus, it will be understood that the ribbon 105 is carried by the truck and is movable therewith when changing from one type-set to another to render the sections of ribbon associated with the type-sets effective.

Each ribbon-vibrator may be actuated, when its associated type-set is effective, to expose the portion of ribbon threaded there-
10 through to the types 92 and 93 of the printing type-bars of said type-set. This may be done by a ribbon-vibrator lever 114, which, when the universal bar 65 of the associated type-set is actuated, swings about its pivot
15 115 through the intermediary of an upwardly-projecting arm 116 on the floating interponent 67, which actuates the dog-rocker of the escapement mechanism. The connection between the lever 114 and the
20 interponent 67 comprises a pin 117 projecting laterally from the lever 114, which engages in a slot 118 in the upwardly-projecting arm 116 of said interponent. Thus, when the interponent 67 is moved rearwardly
25 during typing operations, the forward end of the ribbon-vibrator lever 114 is moved upwardly to bring the ribbon 105 into the path of the printing types 92 and 93.

The ribbon-vibrator levers 114 may be
30 connected, one at a time, with the interponent 67 when the associated type-set is rendered effective. To do this, they are slidingly supported on their pivot 115 in the form of a fulcrum-rod which is secured
35 by ears 119 to the shift-rail 100, so that the levers 114 may be moved sidewise of the machine to connect either one with the interponent 67. To assist in moving the ribbon-vibrator levers 114 with their associated
40 type-sets, when changing from one type-set to another, there is provided for each lever 114 a bracket 120, embracing the latter, and which is secured to the associated type-bar segment 17.

45 To illustrate more clearly the changing from one type-set to the other and the connecting and the disconnecting of the ribbon-vibrator levers 114 with the interponent or actuator 67 during such operation, let it be assumed that the type-set 10^a is to be rendered effective. The operative first unlocks the type-carrying truck 19, by means of the handle 41, as hereinbefore described. He then moves the type-carrying truck 19 toward the right-hand side of the machine by means of the finger-piece 22. During the early part of this movement, the pin 117 on the ribbon vibrator lever 114, associated with the type-set 10, leaves the slot 118 in the
50 arm 116 of said interponent, Fig. 3. During the latter part of the movement of said truck 19, as the type-set 10^a approaches its effective position, the pin 117 on the ribbon-vibrator lever, associated with said type-

set, enters the slot 118 in the arm 116, after 65 which the stop 49 on the truck engages with the pawl 38, to position said type-set 10^a, and the pawl 38 then drops into the slot 40, thus locking the type-carrying truck 19 in its changed position.

70 To facilitate the entrance of the pins 117 into the slot 118 of the arm 116 of the interponent 67, said pins may be slightly pointed at their free ends.

During case-shifting movements of the 75 platen 11, the ribbon-vibrator 108 of the effective type-set moves therewith, so as to maintain the same normal relation between the platen and the section of ribbon at the typeguide 109. To do this, the fulcrum-rod 80 115 for the ribbon-vibrator levers 114 is moved with the shift-rail, through the intermediary of the ears 119, during case shifting operations, thus carrying with it said levers 114, and consequently the effective ribbon-vibrator 108. To guide the ribbon-vibrator lever substantially parallel to itself during this movement, so that the forward end thereof raises or lowers the ribbon-vibrator 108, the slot 118 in the upwardly-projecting 90 arm 116 of the interponent 67 is vertically disposed and elongated, so as to allow the pin 117 on the ribbon-vibrator lever 114 to move up and down therein, thus guiding the connected lever.

95 It will be understood that only one ribbon-vibrator 108 is connected with the interponent 67 at a time, and that the disconnected ribbon-vibrator 108 would have a tendency to drop relatively to the type-bar 100 segment. To avoid this, each ribbon-vibrator 108 is provided with ears 121, bent forwardly therefrom, and which normally rest on the base of the type-guides 109, and also engage with the sides of said type-guides, so as to be guided thereby, during vibrations thereof.

105 It will further be seen that only the connected ribbon-vibrator 108 will be raised with the platen 11 during case-shifting 110 movements of the same, the other ribbon-vibrator remaining in its lowermost position; but, as the fulcrum 115 moves up during case-shifting of the platen, the rear part 115 of the ribbon-vibrator lever 114, associated with the last-mentioned ribbon-vibrator, swings, thus moving the pin 117 thereon out of register with the slot 118. If the operative should change from one type-set to another, while the platen is in the upper-case 120 position, I have provided means to guide the pin into the slot 118. This may include cams 123 at either side of the arm on the interponent to guide the pin 117 properly into the slot 118, thus establishing the connection of the ribbon-vibrator of the type-set being rendered effective with the interponent or actuator, and at the same time raising

said ribbon-vibrator 108 so that the ribbon 105, carried thereby, bears the proper relation to the platen.

To avoid lifting the ribbon-vibrator levers 114 out of engagement with their respective guide-brackets 120, when the platen is being shifted to upper-case position, I have provided each guide-bracket with upwardly-projecting ears 124. These ears are of such a length that they will retain therebetween their associated ribbon-vibrator-levers 114 when they are in their upper-case positions.

The ribbon 105 may be fed from one to the other of the spools 106, during the typing, by means of the downwardly-extending arm 91, comprising part of the swinging frame 82 which is actuated through the intermediary of the floating interponent 67 by either one of the universal bars 65, as hereinbefore described. The free end of said arm has a slot 125, through which extends a rod 126 between two arms 127, projecting rearwardly from a rock-shaft 128, so that the latter may be actuated by the arm 91, thereby vibrating a pawl 129 engaging with a ratchet-wheel 130 on a main ribbon-feed shaft 131, carried by truck 19, thus causing rotary movements of the latter; said pawl 129 being mounted on an arm 132 projecting forwardly from, and secured to, said rock-shaft 128. A holding pawl 133 engages with said ratchet-wheel 130 to prevent backward rotation thereof. It will be understood that the ribbon-feeding pawl 129 is vibrated back and forth, at each printing operation, through the intermediary of the type-bars 12 which engage with the universal bars 65. The rotary movements of the main ribbon-feed shaft 131 are transferred through beveled gears 134 thereon to drive the vertical countershafts 135, upon which the ribbon-spools 106 are mounted, through the intermediary of beveled gears 136 arranged at the lower ends of said vertical countershafts. It should be understood that there are two sets of the gears 134, 136, and that only one set is in mesh at a time; and that the main ribbon-feeding shaft is slideable lengthwise in the type-carrying truck to connect either one of the gears 134 thereon, with its associated gear 136 on the vertical counter-shaft or ribbon-spool shaft 135.

From the foregoing, it will be understood that either type-set, when in effective relation with said keys, may be effective to actuate the ribbon-feeding mechanism, and that the rod or cross-bar 126 is carried by the type-carrying truck 19, and is movable relatively to the downwardly-projecting arm 91, at which time the cross-bar 126 slides relatively to said downwardly-projecting arm 91 through the slot 125 in the latter.

In illustrating my invention, I have shown it as applied to the Underwood typewriting

machine, some of the standard parts of said machine being changed for the purpose of applying my invention.

Variations may be resorted to within the scope of the invention, and portions of the improvements may be used without others. 70

Having thus described my invention, I claim:

1. In a typewriting machine, the combination of two ribbon vibrators, arranged side by side transversely of the machine, each 75 having an actuating lever, an actuating element, adapted to coöperate with either of said levers, and means for moving said levers and said ribbon vibrators sidewise to connect said levers one at a time with said actuating element and to concomitantly bring the ribbon vibrators to the printing point. 80

2. In a typewriting machine, the combination with a platen, of two ribbon-vibrators spaced apart transversely of the machine, ribbon-vibrator-levers for said ribbon-vibrators, a common fulcrum for the latter, a single actuator for said ribbon-vibrator-levers, said actuator being adapted to engage with either ribbon-vibrator-lever but 90 only one at a time, and means to cause a relative movement between said ribbon-vibrator-levers and said actuator to render either ribbon-vibrator effective and to bring it to the printing point. 95

3. In a typewriting machine adapted to print at a single printing point, in combination, a plurality of ribbon-vibrators spaced apart transversely of the machine, a carriage on which said ribbon-vibrators are 100 mounted, said carriage being movable transversely of the machine to bring any one of said ribbon-vibrators to a position for use at said printing point, a lever connected with each of said ribbon-vibrators and movable therewith transversely of the machine, and a single actuator for said levers adapted to coöperate with any one of them when the corresponding ribbon-vibrator is brought to effective position adjacent the printing 110 point. 105

4. In a typewriting machine, in combination, a platen, two ribbon-vibrators spaced apart transversely of the machine, a lever connected with each of said ribbon-vibrators 115 to actuate the same, projections on the adjacent sides of the two levers, an actuating member between said levers and provided with a slot adapted to receive either of said projections, means to cause a relative movement, transversely of the machine, between said ribbon-vibrators and levers on the one hand and said actuating member on the other, case-shift mechanism adapted when shifted to upper case to raise the pivots of 120 said levers, and cams on the opposite sides of said actuating member adjacent said slot so as to insure entrance therein of said pro- 125

jections in case such relative movement between the ribbon-vibrators and levers and the actuating member is effected when the case-shift mechanism is in upper-case position.

5. In a typewriting machine, in combination, a platen carriage, two type segments side by side transversely of the machine, a set of type-bars in each segment adapted to 10 be swung to a point substantially at the center of the corresponding segment, a universal bar supported on each of said segments, a ribbon-vibrator supported on each of said segments, a segment carriage supported for 15 movement transversely of the machine to bring either segment and the corresponding vibrator to the printing point, a lever connected to each vibrator and loosely mounted on a transverse rod to be slid therealong, devices 20 embracing said levers adjacent said rod and connected with said segment-carriage to cause the levers to move therewith, and an actuator positioned behind the printing point and adapted for operative engagement 25 with the universal bar and the lever corresponding respectively to the segment and ribbon-vibrator brought to the printing point.

6. In a typewriting machine, in combination, a platen carriage, two type segments side by side transversely of the machine, a set of type-bars in each segment adapted to 30 be swung to a point substantially at the center of the corresponding segment, a universal bar supported on each of said segments, a ribbon-vibrator supported on each of said segments, a segment-carriage supported for movement transversely of the machine to bring either segment and the corresponding vibrator to the printing point, a lever connected to each vibrator and loosely mounted on a transverse rod to be slid therealong, devices 35 embracing said levers adjacent said rod and connected with said segment-carriage to cause the levers to move therewith, an actuator positioned behind the printing point and adapted for operative engagement with the universal bar and the lever corresponding respectively 40 to the segment and ribbon-vibrator brought to the printing point and a platen-carriage-escapement mechanism operable by said actuator.

7. In a typewriting machine, the combination with a ribbon carrier and a vibrator, of an actuator adapted to be engaged therewith, means for shifting them relatively to

each other, a type segment, and a bracket on the segment embracing the vibrator.

8. In a typewriting machine, the combination with a ribbon carrier and a vibrator, of an actuator adapted to be engaged therewith, means for shifting them relatively to each other, a type segment, a case shift device on which the vibrator is pivoted, and a bracket on the segment adapted to guide the vibrator during the case shifting operation.

9. In a typewriting machine, in combination, a platen carriage, a type segment movable to and from effective position with respect to the printing point, type-bars journaled in the segment, a universal bar supported on the segment and operable by said type-bars, a separately supported ribbon actuator actuatable by the universal bar only when the segment is in effective position, and an escapement for the carriage actuatable by the actuator.

10. In a front strike typewriting machine, the combination with a type segment and a platen carriage, of type bars journaled in the segment, a universal bar supported on the segment and operated by said type bars, a ribbon actuator behind the universal bar, a rocker behind the actuator to support it, a second rocker supporting its front end, and an escapement for the carriage operated by the actuator.

11. In a front strike typewriting machine, the combination with a type segment and a platen carriage, of type bars journaled in the segment, a universal bar operated by the type bars, a pair of rockers on the segment supporting the universal bar, a ribbon actuator, a pair of rockers supporting said actuator, and an escapement actuated at each actuation of the universal bar.

12. In a front strike typewriting machine, the combination with a type segment and a platen carriage, of type bars journaled in the segment, a universal bar operated by the type bars and carried by the segment, a separately supported ribbon actuator, an abutment on the universal bar, a co-operating abutment on the actuator whereby the bar operates the actuator, an escapement for the carriage, and an abutment on the actuator adapted to operate the escapement.

JOHN WALDHEIM.
